UNITED STATES PATENT OFFICE.

ROBERT H. HENDERSON, OF EAST ORANGE, NEW JERSEY, ASSIGNOR TO WESTINGHOUSE LAMP COMPANY, A CORPORATION OF PENNSYLVANIA.

INCANDESCENT LAMP.

1,075,475.

Specification of Letters Patent.

Patented Oct. 14, 1913.

Application filed February 3, 1911. Serial No. 606,428.

To all whom it may concern:

Be it known that I, ROBERT H. HENDERSON, a citizen of the United States, and a resident of East Orange, in the county of 5 Essex and State of New Jersey, have invented a new and useful Improvement in Incandescent Lamps, of which the following is a specification.

My invention relates to electric incandescent lamps, and particularly to supporting means for the filaments thereof.

The object of my invention is to provide a support for lamp filaments, and a method of applying filaments thereto, whereby 15 lamps may be more expeditiously and economically manufactured and the proper relations between the filament and the support may be more readily obtained than with structures and methods heretofore provided.

In electric incandescent lamps having tungsten or other metallic filaments, the filaments are usually bent around and supported by anchor wires having hooks at 25 their ends to receive the same. In the manufacture of such lamps the winding of the filaments upon the supports naturally results in a close engagement between the filaments and the anchors and the subject- 30 ion of the filaments to tension and the anchors to a bending strain, all of which it is desirable to modify and relieve before the completion of the lamps. In fact, it is usually desirable to provide for a com- 35 paratively free and loose support of the filament, and to that end it has heretofore been customary to give the anchor wires a permanent set by bending after the application of the filament thereto. This is ob- 40 viously a delicate operation to perform and one that is attended with no small degree of danger of breakage of the filament. Moreover, it is difficult to obtain uniformity in the adjustment of the anchors with re- 45 spect to the filaments. The anchor and method of the present invention avoid the necessity of bending or otherwise adjusting the anchors after the filament is applied thereto, and results in uniformity of the

relations of the filament to its supports as 50 well as in a material lessening of breakage and expense in manufacture.

In Figure 1 of the accompanying drawing, which illustrates, in perspective, the internal parts of a partially completed lamp 55 embodying my invention, a filament 1 is bent back and forth around a plurality of anchors or supports 2 that project laterally from a central arbor 3. The anchor wires at one or both ends of the lamp, 60 though preferably only at the end remote from the leading-in wires, are bent to provide hooks near their free ends for the reception of the filament, and the end portions thereof beyond the hooks are initially 65 bent backwardly across the open portions of the hooks to provide guards around which the filament is wound during its application to the anchors. The filament may be wound freely and rapidly around the 70 guard portions of the anchors without regard for the final relation which the filament and anchors should bear to each other. After the filament has been completely applied to the supports, the guards are sev- 75 ered from the remaining portions of the anchors, leaving the filament occupying the open portions of the hooks and only loosely engaged thereby. Thus, in the completed lamp the filament is loosely supported by 80 the anchor wires, and the degree of looseness is the same between the filament and all of its supports. The former delicate operation of adjusting the supports to secure this looseness is also avoided, and lamps 85 may be expeditiously and economically manufactured.

Fig. 2 shows a modification of the anchor of Fig. 1, the end portion of the anchor wire extending only partly across the open 90 portion of the hook, but providing a sufficient support for the filament during the operation of winding.

Many other modifications may obviously be made within the spirit and scope of the 95 invention, and I intend that all such should be included within the scope of the appended claim.

I claim as my invention:

The method of manufacturing an incandescent lamp which consists in applying a filament to a support having a hook to receive the filament and a guard for the hook, and then removing the guard.

In testimony whereof, I have hereunto

subscribed my name this 18th day of January 1911.

ROBERT H. HENDERSON.
